Inventor:
Clarence Holmes Kelsea

UNITED STATES PATENT OFFICE.

CLARENCE HOLMES KELSEA, OF BELMONT, MASSACHUSETTS.

VALVE MECHANISM FOR OIL-CANS.

1,380,973.

Specification of Letters Patent. Patented June 7, 1921.

Application filed September 30, 1918. Serial No. 256,339.

To all whom it may concern:

Be it known that I, CLARENCE HOLMES KELSEA, a citizen of the United States, residing in Belmont, county of Middlesex, State 5 of Massachusetts, have invented certain new and useful Improvements in Valve Mechanism for Oil-Cans, of which the following is a specification, reference being had to the drawings accompanying the same and forming 10 a part thereof.

My invention relates to valve mechanism for oil cans.

The objects of my invention are as follows:—to provide a valve mechanism for oil 15 cans having a valve operating device conveniently located to the hand of the user provided with a guide which will prevent the mechanism from binding and also prevent the leakage of oil through the guide.

20 In the drawings—

Figure 1 represents a sectional elevation of an oil can having my improved valve mechanism attached thereto.

The improved valve mechanism herein 25 illustrated is applied to oil cans of the type used by engineers and oilers in oiling the bearings of machinery and such as is usually provided with a long nozzle so that the user can reach in through complicated machinery 30 to bearings located where they are not easily accessible to the hand of the user.

In the drawings, 1 represents a body of an oil can, which is of the usual construction, and 2 illustrates the nozzle, the same being 35 in section with a portion of its end broken away so as to readily illustrate the device on the usual size sheet of drawing paper. 3 represents a handle of the usual type attached to the body of the oil can and located 40 at a convenient distance from the valve operating mechanism. 4 illustrates the filler tube for filling the can and 5 is a cap to cover the filler tube. The valve 6 may be a ball made of brass or other suitable non-corrosive 45 material of a size to seat upon the valve-seat 7. Said valve-seat 7 is located near the outlet to the nozzle of the can. The valve 6 is held in a closed position by the valve operating rod 8. The operating rod 8 has secured 50 to it a collar 9 serving as a seat for one end of the spring 10, the other end of the spring 10 contacting with the fixed seat 11 which is secured to the body of the can. The lower

end of the rod 8 has a hook portion 12 which embraces the circular indentation 13 of the 55 valve operating lever 16 in such manner that downward movement of the valve operating lever 16 will move the valve rod 8 endwise to unseat the valve 6 of the seat 7. The inner end of the lever 16 is provided with an 60 angular hook portion 14 which hooks into a hole in a bracket 15, the bracket 15 being secured to the body 1 of the can. A guide 17 is provided, which is curved with the hole in the bracket 15 as the center of the curvature so that the curved portion of the lever 16 which has the same curvature as the guide 65 17 will slide freely therein and be guided thereby. The lever 16 is also provided with a stop-collar 18 secured at the upper end of 70 the curved portion so as to limit its downward movement. There is also provided a finger-piece 19 formed upon the outturned end of the lever 16 and so located as to be operated, preferably by the index finger or 75 thumb of the user.

In the types of valve operating mechanism for cans of this description heretofore made, the levers have not been properly guided, so that they were liable to stick and 80 not close the valve, thereby causing a waste of oil. In the valve mechanism provided herein there is no liability of the valve mechanism sticking as the lever operating the valve is so constructed and the guide so 85 made that it will operate freely and so that a spring of light tension will serve to properly close the valve when the pressure on the operating lever 16 is released.

Having described my invention what I 90 claim is—

The combination with an oil can provided with a substantially long nozzle, of a valve located in said nozzle to close the same, a rod extended into said nozzle and coöoperating 95 with said valve to close the same and having its lower end extended into said can, a lever pivoted within the can at one side of said nozzle and extended across said can and provided on the opposite side of said nozzle with 100 an upwardly extended curved portion whose center is the pivot of said lever, a curved guide through which said curved portion is movable, means for connecting the valve closing rod with the said lever between the 105 curved portion thereof and the pivot there-

for to effect downward movement of the valve in said nozzle by downward movement of said curved portion, and a spring to move said rod upwardly to close said valve.

In testimony whereof, I have hereunto set my hand, in the presence of two subscribing

witnesses, this the 13th day of Sept. A. D. 1918.

CLARENCE HOLMES KELSEA.

Witnesses:

D. BAKER,
H. M. KELSO.
